CONSTRUCTION OF LEAD CHAMBERS FOR
THE MANUFACTURE OF SULPHURIC
ACID

René Moritz, Chatou, France

Application August 31, 1931, Serial No. 560,525
In France September 3, 1930

3 Claims. (Cl. 23—284)

High chambers with bottom communications have given very interesting results in that the reactions in these chambers are considerably speeded up and that without artificial or costly means and without an excessive circulation of oxide of nitrogen, a considerable production is obtained per cubic metre of chamber space, and also per kilogram of lead employed in the construction.

Up to the present time it has only been possible to construct relatively small units with this arrangement. It had been thought possible to increase the dimension of the pieces of apparatus by sending the gases issuing from the Glover tower into two or more series of parallel chambers, as shown in the drawing of French specification No. 571,206 of the 27th September 1925 in the names of R. Moritz and A. Sonneck. Practice has shown that it was impossible to obtain complete uniformity in this way and that sometimes one set worked faster and sometimes another, without any apparent reason. For this reason it is not possible to obtain the whole useful effect from the chambers and the consumption of oxide of nitrogen increases when it is sought to produce as much per cubic meter of chamber space in such apparatus with a plurality of series of chambers as in apparatus having a single series.

The object of the present invention is to overcome these disadvantages.

Considerable study has shown that it is possible to construct very large chamber systems based on the principle of high chambers provided with bottom communications described herein-after, in which all the chambers are in series and produce very considerable quantities of acid per cubic metre of chamber space on the order of 12 kilograms of acid calculated on monohydrated acid, while consuming only 0.8 to 0.9 kilogram of nitric acid of 36° Bé. per 100 kg. of monohydrated sulphuric acid, on condition that the ratio between the surface of the chamber walls in square metres and the volume of the chambers in cubic metres remains in the neighbourhood of one to one and does not exceed in any case 1.2 to 1.

By working in this manner, it is possible to construct chambers from 15 to 25 metres high, 5, 10, 15, 20, 25 metres and more long, and 2.50 to 5 metres in width; this width may be as small as permissible by the use of atomizers or other means for introducing water in a finely divided state.

Five to ten or more of these chambers are assembled together by means of short, very wide

ducts connecting the lower part of one chamber with the lower part of the next. The gases from the reaction and the acids produced pass through these channels. The length of the channels is the same as that of the chambers, consequently 5 5, 10, 15, 20 and 25 metres. This arrangement, hitherto unknown, gives novel results, but requires special precautions to be taken.

In the accompanying drawing:

Figure 1 represents a perspective view in part 10 section of the apparatus showing the bottom communications for the passage of the gases interrupted; and

Figure 2 is a similar view of a modification with 15 special ducts.

If we examine how the gases circulate in a high 20 chamber with a bottom communication, we will see that the stream of gas under reaction which enters the chamber rises at 1 (Figures 1 and 2), while exchanging and combining by turbulent 25 movements its heat, its oxide of nitrogen, its sulphur dioxide and its water with the descending streams of gas at 2 and 3. Consequently, only the relatively more exhausted of the gases issue from the chamber after having given up their heat in 30 contact with the walls, which has made them heavier. But the gases which descend so as to form the gas stream 2 are compelled to pass through the ascending gas stream 1 in order to pass 35 through the bottom communication 8, which is difficult; these gases are thus compelled to pass round the gas stream 1 and pass at the side.

With the bottom communications of square or 40 round chambers this does not present any difficulty, but with very large chambers the path 35 to be followed by the gas stream 2 becomes too long and irregularities are produced. It is therefore necessary to employ means to avoid these irregularities.

It is possible to do this by causing the stream 45 2 to penetrate the stream 1 by providing ducts which cause the gas stream 2 to pass through the gas stream 1 and rejoin the gas stream 3. The figures show the path of the gases when such ducts are provided in the chambers and the bottom 50 communications are also interrupted. These ducts may be formed by small walls 6—6 made of acid proof bricks or other materials withstand- 55 ing the local conditions. These walls are cov- ered by slabs 7 and allow the gas stream 2 to pass through the gas stream 1. If the spaces between the ducts are not too large, these ducts answer the purpose perfectly. The bottom com- munication may also be interrupted in width

every four or five meters by partitions, thus di- 55

viding the stream of gases into several streams end to end. Figure 1 shows the path of the gases in an arrangement in which the bottom communications are interrupted in width without providing the above-mentioned ducts. The ascending gas stream then allows room, where the interruptions occur in the communications for the descending gas stream to pass, and the apparatus works extremely uniformly. The gas streams do not become mixed, but remain in contact for effecting the exchange of oxide of nitrogen, water, sulphur dioxide, etc. by diffusion, as explained above. The gases become classified by order of activity; the more exhausted gases leave the chamber alone in order to pass below the next bottom communication 8.

The very large surface of contact between the gases and the acids from the bottom of the lead chamber passing through the bottom communications gives, by the simplest possible means, moments of reaction which are still further increased by the fact that, in order to cool the gases from the chambers effectively, it is necessary to make the corridors 9 between the chambers much larger. There is therefore a very large surface where the reactions are considerably activated, so that with very little oxide of nitrogen in circulation, a much greater number of reactions is obtained than in the chambers of usual construction. Moreover, the whole of the production of acid is made to circulate towards the head chamber from which the whole of the production is drawn off. Consequently, the oxide of nitrogen is strongly absorbed by the tail acids, in the presence of the gases poor in sulphur dioxide but rich in oxide of nitrogen. These very nitrous acids are completely de-nitrified at low temperature in the bottom head communications where they are in contact with the gases rich in sulphur dioxide which have still undergone little reaction. As a result, the oxide of nitrogen is returned strongly into circulation in the interior of the chambers through the medium of the acid from the bottom of the lead chambers.

Although the work is carried out at a relatively low temperature and with little oxide of nitrogen in circulation, an intensity of production is obtained which is greater than the most intense productions obtained with hitherto known apparatus which require a very considerable circulation of oxide of nitrogen. The practical result is that, with relatively little oxide of nitrogen in circulation, the relative dimensions of the Gay-Lussac tower and, consequently of the Glover tower can be reduced and that as the de-nitrification takes place to a larger extent in the chambers, at low temperature, instead of being effected in the Glover tower, at high temperature, the effective consumption of oxide of nitrogen is considerably reduced because the reaction at low temperature does not produce a decompositon of oxide of nitrogen, that is to say oxides of nitrogen having variable compositions from N_2O_3 to NO_2 which are reduced to N_2O and N when the de-nitrification takes place at high temperature in the Glover tower or in

the ordinary so-called intensive working chambers.

An abbreviated description of the operation of this apparatus is here given.

Referring to Figure 1, this shows a series of two or more intercommunicating reaction chambers each with a plurality of flat, wide ducts 8 parallel to the length direction of the chambers. These chambers are of considerable height and length but of narrow width and their bottoms are covered with a thin layer of acid. The leading-in ducts are partly filled with the acids so that the reaction gases can pass over them into the reaction chambers and over the layer of acid therein thus becoming heated, and travel in an upward stream 1 within the chamber and heat its walls. This upward gas stream thus becomes heavier when reaching the top of the chamber and then reverses its motion forming a downward stream 2 and 3. The stream 1 exchanges and combines its heat and content of oxide of nitrogen, sulfur dioxide and water with the downward stream of heavy reaction gases as at 2 and 3, said two streams thus running in counter current.

The first and second as well as the second and third chambers are connected by similar flat, tubular ducts 8, so that the descending cooled and exhausted gas streams 2, 3 from the first chamber pass through the ducts 8 into the second chamber and similarly from the second chamber to the third and so on.

As the ascending gas stream 1 may interfere with the easy passage along the bottom of the chamber of a descending gas stream 2 near the inlet duct 8, additional conduits 7 may be provided as in Fig. 2, to lead the gas stream without interference and more directly to the exit opening and through ducts into the second chamber. Since enough space is provided above the level of the acid layer, to permit the reaction gas to sweep over it, no bubbles are formed by the gas.

What I claim is:

1. Lead chambers for producing sulphuric acid, said chambers being very high, very long and of small width, slot-like conduits interconnecting the lower parts of the said chambers, said conduits extending horizontally over the whole length of the chambers, thus permitting reaction gases to pass through the conduits just above the acids, the ratio of the area of the chamber walls in square meters to the volume of the chamber in cubic meters being about 1 to 1 and not exceeding 1.2 to 1.

2. Lead chambers as claimed in claim 1 in which ducts are provided between the conduit sections within the chambers and in the spaces between said conduits, said ducts being partly open on the top.

3. Lead chambers as claimed in claim 1, in which ducts are provided between the conduit sections within the chambers and in the spaces between said conduits, said ducts being partly open on the top, said ducts being formed by two vertical walls and a superposed horizontal wall.

RENE MORITZ.
